(57) **CLAIM**

The ornamental design for an electric vehicle charger with single opening for connector of an electric cable, as shown and described.

DESCRIPTION

FIG. 1 is a perspective view of an electric vehicle charger with single opening for connector of an electric cable;

FIG. 2 is a front view of the electric vehicle charger with single opening for connector of an electric cable;

FIG. 3 is a rear view of the electric vehicle charger with single opening for connector of an electric cable;

FIG. 4 is a right side view of the electric vehicle charger with single opening for connector of an electric cable;

FIG. 5 is a left side view of the electric vehicle charger with single opening for connector of an electric cable;

FIG. 6 is a top view of the electric vehicle charger with single opening for connector of an electric cable;

FIG. 7 is a bottom view of the electric vehicle charger with single opening for connector of an electric cable;

FIG. 8 is an enlarged front view defined by the ranges A-A and B-B of FIG. 2;

FIG. 9 is an enlarged cross-sectional view defined by the ranges A-A and B-B of FIG. 2 and the range M-M of FIG. 4 and taken along the line C-C of FIG. 8;

FIG. 10 is an enlarged top view defined by the ranges D-D and E-E of FIG. 6; and,

FIG. 11 is an enlarged perspective view defined by the ranges X-X and Y-Y of FIG. 1.

The broken line showing of a body, a connector and an electric cable is for the purpose of illustrating unclaimed portions of the electric vehicle charger and forms no part of the claimed design.

The electric vehicle charger includes, a body, an electric cable extending from the body and a connector provided at an end of the electric cable. As shown in the perspective view, the connector is supported by the body via an opening which is formed in an inclined surface of an upper part of the body.
